Primary Examiner — Karen E Kearney*Assistant Examiner* — Adam C Mager(57) **CLAIM**

The ornamental design for an exhibition table, as shown and described.

DESCRIPTION

FIG. 1 is a perspective view of an exhibition table showing my new design;

FIG. 2 is a front view thereof;

FIG. 3 is a left side view thereof;

FIG. 4 is a right side view thereof; and,

FIG. 5 is a top view thereof.

The bottom and rear views of the exhibition table are flat and include no surface ornamentation.

The broken lines in the figures show portions of the exhibition table that form no part of the claimed design.

1 Claim, 5 Drawing Sheets(56)
